FLUTED PERFORATING PUNCH DEVICES
OR TOOLS

John F. Kopczynski, North Tonawanda, N. Y.

Application December 6, 1955, Serial No. 551,376

7 Claims. (Cl. 164—124)

This invention relates to punch devices or tools for perforating sheet material, and especially to the piercing punch itself.

An object of the invention is to provide an improved punch device for perforating sheet material, with which the piercing element will effectively pierce the sheet material and in its reciprocations may be guided by the stripper plate with which the piercing element may operate for unusually long periods of use without breakage, and which requires little modification of existing machines for perforating sheet material.

Another object of the invention is to provide a piercing element for perforating punch devices which will be exceptionally durable and practical in use, of relatively long operating life, have maximum strength in resisting breakage during a punching operation, which may be made of one integral piece of metal and directly from a hardened blank without causing the blank to lose its hardness, which will produce clean apertures, and which will be relatively simple, effective and inexpensive.

A further object is to provide an improved, practical, simple and relatively inexpensive method of forming piercing elements or punches for perforating sheet material from an integral blank of metal, and with which the elements will have maximum resistance to breakage in use and an integral guide and reinforcement at the portions where breakage is most likely to occur in use.

Other objects and advantages will be apparent from the following description of one embodiment of the invention and one application of the method, and the novel features will be particularly pointed out hereinafter in connection with the appended claims.

In the accompanying drawings:

Fig. 1 is a sectional elevation of a punch device made in accordance with this invention and illustrating in elevation the perforating element of this invention at the start of a perforation;

Fig. 2 is a perspective of the new perforating element;

Fig. 3 is an end elevation of the same;

Fig. 4 is a longitudinal, sectional elevation of the same;

Figs. 5, 6 and 7 are horizontal, sectional plans of the same, the sections being taken on lines 5—5, 6—6 and 7—7 respectively;

Fig. 8 is a side elevation of a grinding wheel that may be employed in the method of forming the perforating element;

Fig. 9 is a sectional elevation, lengthwise of the perforating element, and illustrating the manner in which the first flute is ground on a hardened punch blank;

Fig. 10 is a vertical, transverse, sectional elevation of the same, the section being taken approximately along the line 10—10 of Fig. 9; and

Fig. 11 is a sectional elevation similar to Fig. 1, but illustrating a modification thereof, without a guide sleeve.

In the embodiment of the invention illustrated in Figs. 1 to 10, the punch device includes an apertured die 1 supported in a recess 2 in a base 3, the base having a passage 4 alined with and larger than the aperture 5

2

of the die 1. The blank B of sheet material to be perforated is disposed upon the top of base 3 over the top of die 1 and is confined thereagainst by a stripper member 6, as usual in punch devices. The stripper member 5 has a liner sleeve 7 therein alined with the die 1, with the passage 8 of the sleeve larger than the aperture 5 of the die 1.

A perforating element or punch 9, shown separately in Fig. 2, has a head 10 which is detachably mounted in a holder 11 in the usual manner. The element 9 is formed of a body of hardened metal, such as hardened steel, and has a cylindrical shank 12 which is slidingly guided in the passage 8 of the liner sleeve 7, as shown in Fig. 1. The free or perforating end or stem 13 of the element 9 has a cross sectional area substantially less than the cross sectional area of the shank 12. The peripheral surface of the stem 13 continues endwise into the adjacent end of the shank 12 as flutes or channels 14 that are arranged at intervals around the periphery of the shank 12 and spaced apart. These flutes 14, after they enter the end of the shank 12, become progressively shallower, with the bottom of each flute in the form of an arc 15 (see Fig. 4) in a plane lengthwise of the shank, and also an arc of a circle 16 in transverse cross section, with the center of curvature of the arc of a circle 16 in the longitudinal axis of the shank, as shown in Figs. 4, 6 and 7.

The flutes 14 intersect with adjacent flutes as they enter the end of the shank 12, as shown in Fig. 5, but become separated by the shank as they progress farther into the shank end, as shown by the sections of Figs. 5, 6 and 7. This provides a plurality of tongues or fingers 17 extending endwise from the shank 12 along the stem and spaced from the stem at their free ends. The outer walls 18 of the fingers 17 are continuations of the cylindrical, peripheral wall of the shank, so that they can slide closely in the passage 8 of the liner sleeve 7, as shown in Fig. 1. It will be noted that the tongues or fingers 17 are free of the stem at the start of each arc 15, but become connected to the bottoms of the flute intermediate of the ends of arcs 15. The body of this element, by reason of the arcs 15, thus progressively increases in cross sectional area from the stem 13 to the unfluted part of the shank 12, and may be considered as a tapered connecting or intermediate part between the stem and the shank.

The preferred method of forming this perforating element or punch 9 is to form the body with the shank and head of the desired size and shape, with an end of reduced diameter for the stem 13. The stem 13 is preferably left slightly larger in diameter than is desired for the final stem, and this stem may be machined in any desired manner to this slightly larger diameter. The punch body is then mounted or chucked for rotation, so that the stem end is free and may be rotated about its longitudinal axis through selected increments of rotation, such as three in this example. While the punch body is so held in one of its angular positions, a grinding wheel 19 is moved along and in contact with the stem 13 from the free end of the stem to its other end attached to the shank, and into the shank to the extent shown by dash lines in Fig. 9. This grinding wheel 19 is mounted in fixed relation on a rotatable shaft 20, Fig. 8, so as to rotate therewith, and this shaft is disposed crosswise of the axis of the stem 13, as shown in Fig. 9 and moved in the direction of the arrow A in Fig. 9 until the rotating grinding wheel 19 reaches the position shown in dash lines in Fig. 9.

The peripheral grinding surface of the wheel 19, in transverse cross section, has the shape of an arc D of a circle (Figs. 8 and 10), whose radius is equal to the radius of the desired radius of the cylindrical surface of the stem. As the wheel 19 moves against the end of

the shank 12, it grinds a flute 14 therein, as shown in Figs. 9 and 10, and at the same time grinds an arc of the desired peripheral surface C of the stem (see Fig. 10). After this operation, the wheel 19 is moved from the stem and the perforating element rotated angularly about its longitudinal axis into a position for another flute to be formed. Then another similar grinding operation is performed on the element which grinds a new arc C on the stem that meets edgewise with the previously formed arc C on the stem, and also forms another flute that intersects with the previously formed flute at the start of the flute, but becomes separated therefrom as the grinding of the flute farther into the shank continues. After this second flute is formed, the element is again rotated into another angular position, and then another flute and arcuate part of the stem are ground in the manner described above. Thus, the entire peripheral surface of the stem is ground to size by the wheel 19 so that the ground tool marks will run substantially lengthwise of the stem and along the bottom of each flute, which straight-ground tool marks on a punching or perforating tool are desirous and advantageous as explained in my prior Patents Nos. 2,604,742 and 2,622,682.

The tapered, intermediate portion of the element resists breakage that usually occurs, if it does occur, at the junction of the stem with the larger shank. The fingers or tongues 17 further absorb some of the shock on the element created during a perforation operation which further reduces danger of breakage of the punch or element, and hence increases the life of the punch. The engagement of the fingers 17 with the liner sleeve also aids in steadyng the punch against breakage stresses in a perforating operation. With this method of grinding, the element, the punch or element can be made directly from a hardened metal blank by simple operations that do not decrease the hardness of the tool.

In the embodiment illustrated in Fig. 11, the perforating element is made as in Figs. 1 to 10, except that the fingers 17 do not engage with the wall of the stripper member, and hence the element is not guided by the stripper member. The fingers 17, however, still perform the function of resisting shock on the tool or element when a perforation of the blank B occurs.

It will be understood that various changes in the details, materials and arrangements of parts which have been herein described and illustrated in order to explain the nature of the invention may be made by those skilled in the art within the principle and scope of the invention as expressed in the appended claims.

I claim:

1. A piercing punch for punching a disc from a sheet blank, which comprises a body having at one end a cylindrical punching stem, a larger diameter shank portion at the other end by which said body may be mounted for endwise reciprocation, and an intermediate connecting portion between said stem and said shank portion, said intermediate portion being tapered from the stem to the shank portion, said shank portion having a plurality of tongues at the junction with the tapered portion extending along the tapered portion and along and spaced from the part of the stem adjoining the tapered portion, the outer surfaces of the tongues being continuations of the peripheral surface of said shank.

2. A piercing punch for punching a disc from a sheet blank, which comprises a body having at one end a cylindrical punching stem, a larger diameter shank portion at the other end by which said body may be mounted for endwise reciprocation, and an intermediate connecting portion between said stem and said shank portion, said intermediate portion being tapered from the stem to the shank portion, said shank portion having a plurality of tongues at the junction with the tapered portion extending along the tapered portion and along and spaced from the part of the stem adjoining the tapered portion,

the outer surfaces of the tongues being continuations of the peripheral surface of said shank, said tongues merging into said tapered portion intermediate the ends of that portion and continuing so merged to the junction of the tapered portion with said shank.

3. A piercing punch for punching a disc from a sheet blank, which comprises a body having at one end a cylindrical punching stem, a larger diameter shank portion at the other end by which said body may be mounted for endwise reciprocation, and an intermediate connecting portion between said stem and said shank portion, said intermediate portion becoming progressively larger in diameter from the stem to the shank portion, said shank portion having a plurality of tongues extending from its junction with the said intermediate portion along that intermediate portion to said stem, the outer surfaces of said tongues being continuations of the peripheral surface of said shank, said tongues being spaced from said stem and the smaller end of said intermediate portion, and merging into said intermediate portion intermediate of the ends of that portion.

4. A piercing punch for punching a disc from a sheet blank, which comprises a body having at one end a cylindrical punching stem, a larger diameter shank portion at the other end by which said body may be mounted for endwise reciprocation, and an intermediate connecting portion between said stem and said shank portion, said intermediate portion becoming progressively larger in diameter from the stem to the shank portion, said shank portion having a plurality of tongues extending from its junction with the said intermediate portion along that intermediate portion to said stem, the outer surfaces of said tongues being continuations of the peripheral surface of said shank, said tongues being spaced from said stem and the smaller end of said intermediate portion, and merging into said intermediate portion intermediate of the ends of that portion.

5. A piercing punch for perforating a sheet blank, which comprises a metal body having at one end a relatively small punching stem, a relatively larger diameter shank portion at the other end by which said body may be mounted for endwise reciprocation, and an intermediate portion connecting the stem to said shank, said intermediate portion having flutes extending from its junction with said stem into said shank to decreasing depth and forming a plurality of fingers arranged in spaced relation to one another about said intermediate portion, and at their free ends spaced from said stem but merging gradually into said body as they approach the unfluted part of said body toward the shank.

6. A piercing punch for perforating a sheet blank, which comprises a metal body having at one end a relatively small punching stem, a relatively larger diameter shank portion at the other end by which said body may be mounted for endwise reciprocation, and an intermediate portion connecting the stem to said shank, said intermediate portion having flutes extending from its junction with said stem into said shank to decreasing depths and forming a plurality of fingers arranged in spaced relation to one another about said intermediate portion, and at their free ends spaced from said stem but merging gradually into said body as they approach the unfluted part of said body toward the shank, the surface of said stem and the bottoms of the flutes in said intermediate portion being ground surfaces with the tool marks of such surfaces running lengthwise of the body.

7. A piercing punch for perforating a sheet blank, which comprises a metal body having at one end a relatively small punching stem, a relatively larger diameter shank portion at the other end by which said body may be mounted for endwise reciprocation, and an intermediate portion connecting the stem to said shank, said intermediate portion having flutes extending from its junction with said stem into said shank to decreasing depths

and forming a plurality of fingers arranged in spaced relation to one another about said intermediate portion, and at their free ends spaced from said stem but merging gradually into said body as they approach the unfluted part of said body toward the shank, said stem and the adjacent part of said shank being cylindrical and the surface of said stem and the bottoms of the flutes in said intermediate portion being ground surfaces with the tool marks of such surfaces running lengthwise of the body.
